UNITED STATES PATENT OFFICE.

MATTHEW GRISWOLD, JR., OF ERIE, PENNSYLVANIA.

DESIGN FOR A GAS HEATING-STOVE.

SPECIFICATION forming part of Design No. 33,092, dated August 14, 1900.

Application filed July 5, 1900. Serial No. 22,633. Term of patent 14 years.

To all whom it may concern:

Be it known that I, MATTHEW GRISWOLD, Jr., a citizen of the United States, residing at Erie, in the county of Erie and State of Pennsylvania, have invented and produced a new and original Design for Gas Heating-Stoves; and I do hereby declare the following to be a full, clear, and exact description of the invention, such as will enable others skilled in the art to which it appertains to make and use the same, reference being had to the accompanying drawing, and to the letters of reference marked thereon, forming part of this specification.

The leading feature of my design for a gas heating-stove consists in the shape, configuration, and ornamentation thereof.

The figure is a perspective view of a gas heating-stove embodying my design.

In the drawing the base-section A of the stove flares outward from the bottom of the fire-box section B, which rests thereon. This base A is generally rectangular in shape and contour, with the corners thereof rounded, and rests upon legs C under the corners thereof. The upper parts of the legs C are circular in shape, corresponding with the rounded corners of the base A, and generally taper toward the feet c thereof and are ornamented on their fronts with raised scroll and foliate work C'. Around the bottom of the base A there is a plain band a, above which the corners thereof are ornamented with scroll and foliate figures a', and the front and ends of the base A, between the corner figures a', are ornamented by raised foliate figures a², springing from the base just above the band a; and across the front of the base A there is a plain foot-rail a³.

The fire-box section B rests upon the top of the base A and is rectangular in shape and extends upward substantially vertical for approximately two-thirds of its height, from which point the front thereof gradually curves inward until it meets the base of the top section D thereof, while the ends are substantially vertical until they meet the base of the section D. The lower or vertical portion of the front of the fire-box B is divided into three rectangular panels B' B² B³. These panels B', B²,

and B³ are provided with oval-shaped openings b', separated by ornamental foliate-work stiles b². The ends of the fire-box section B consist of single panels B⁴, having rounded tops extending up to the base of the section D, and are provided with oval-shaped openings b³, separated by ornamental foliate-work stiles b⁴.

The corners of the upper portion of the section B round from the ends into the curved front section and are ornamented with raised foliate-work b⁵, and the curved portion of the front is formed into three panels B⁵, B⁶, and B⁷, corresponding to the panels B' B² B³ below.

The central of these panels B⁶ is rectangular, and the panels B⁵ and B⁷ have their outer upper corners cut away by the foliate corner-work b⁵. These panels all have oval-shaped openings b⁶, separated by ornamental foliate-work stiles b⁷. The base of the top section D is provided with a plain band d, from which it curves upward and inward to the top thereof, which has a narrow plain band d' between the bands d and d'. This section is ornamented by raised foliate and scroll work d². From the top of the section D five vertical pipes E E F F and G rise, upon which the top section H rests. These pipes are oval in cross-section and are ornamented with beads e near the bottom thereof, and the central pipe G is provided with an ornamental plate g, substantially shield-shaped, ornamented with foliate-work g'. Near the upper ends of these pipes are beads f, and just below where the pipes meet the top section H they are ornamented with ornamental scrollwork figures f'.

The top section H is generally rectangular in shape, with the corners thereof rounded, and overhangs the tops of the pipes E E G F F, entering the bottom thereof, and around the lower edge thereof there is a plain band h, above which the top curves upward and inward to a plain vertical band h', the edge of the flat top thereof, the surface of the top H between the bands h and h' being ornamented with raised scroll and foliate work h². Upon the central part of the top H of the stove there is an ornamental urn I, the base of which is made of open-work I', and the handles ii there-

on are of the Egyptian style of ornamentation. Otherwise the ornamentation of the urn I is of the conventional style.

Having thus described my design, what I claim is—

The design for a gas heating-stove, substantially as shown and described.

In testimony whereof I affix my signature in presence of two witnesses.

MATTHEW GRISWOLD, JR.
